(57) **CLAIM**

The ornamental design for a toilet waste connector, as shown and described.

DESCRIPTION

FIG. 1 is a rear perspective view of the toilet waste connector showing our new design;

FIG. 2 is a front perspective view thereof;

FIG. 3 is a top plan view thereof;

FIG. 4 is a rear elevational view thereof;

FIG. 5 is a right hand side elevational view thereof;

FIG. 6 is a bottom plan view thereof;

FIG. 7 is a front elevational view thereof; and,

FIG. 8 is a left hand side elevational view thereof.

The broken line shown in FIGS. 3 and 4 is included for the purpose of illustrating portions of the article and forms no part of the claimed design.
